UNITED STATES PATENT OFFICE.

RAYMOND P. ZENTS, OF OMAHA, NEBRASKA.

CONCRETE INSERT.

Application filed April 27, 1920, Serial No. 377,035. Renewed May 21, 1923.

To all whom it may concern:

Be it known that I, RAYMOND P. ZENTS, citizen of the United States, residing at Omaha, in the county of Douglas and State of Nebraska, have invented certain new and useful Improvements in Concrete Inserts, of which the following is a specification, reference being had therein to the accompanying drawing.

10 My invention relates to concrete inserts and has for its principal object a device of simple construction which may be inserted in and securely held in the concrete for supporting piping, shafting, and the like.

15 Another object resides in constructing the insert in such a manner that a strap may be secured thereto and engage over a reinforcing rod embedded in the concrete.

20 A further object consists in providing means for temporarily attaching the insert to the form board.

With these and other objects in view, my invention consists in the novel details of construction and arrangement of parts 25 which will be more clearly understood from the following specification and drawings, in which—

Fig. 1 is a front elevation showing the insert with one form of attaching strap;

30 Fig. 2 is a top plan of the insert;

Fig. 3 is a bottom plan of the insert;

Fig. 4 is a longitudinal vertical section through the insert;

Fig. 5 is a front elevation showing another 35 embodiment of the attaching strap;

Fig. 6 is a side elevation showing the further embodiment of the attaching strap, and

Fig. 7 is a front elevation of still another 40 embodiment of the attaching strap.

In the drawings, 1 indicates the form board upon which the concrete 2 is adapted to be poured. My insert is indicated at 3 and is exteriorly tapered so that the top is of greater size than the bottom and the front 45 face is preferably rounded. By tapering the insert the concrete will set therearound and securely hold the insert in position. A threaded socket 4 is formed in the bottom of the insert and a transversely extending slot

50 5 is formed from one side, above the socket, and terminates a short distance from the opposite side. A vertical opening 6 is formed from the top of the insert and leads to the socket 4 as more clearly illustrated in Fig. 4 55 of the drawings.

A nail 7 is adapted to be passed through

the opening 6, extends through the socket 4, and enters the form board. This nail 7 is used for temporarily attaching the insert to the form board prior to the pouring of the 60 concrete.

A perforated flexible strap 8 is inserted through the slot 5 and will be held between the closed end of the slot and the nail 7. The strap is adapted to be bent and embedded in 65 the concrete, and in the preferred embodiment of my invention the ends of the strap will be bent around a reinforcing rod embedded in the concrete.

In Fig. 1 of the drawings, I have illustrated two reinforcing rods 9 arranged parallel and the ends of the perforated strap 8 are bent around these rods and extend downwardly in a vertical position as shown at 10.

In Fig. 5 I have illustrated only a single 75 reinforcing rod 11 and the ends of the strap 8 are bent over the rod in opposite directions to form the diagonally extending ends 12 in opposite directions. In Fig. 6 I have also illustrated a single rod 13 and the strap 8 is 80 bent to form an angular extension 14 the end of which is bent over the rod 13 and downwardly to form an extension 15 extending parallel with the extension 14.

In that form of the invention illustrated 85 in Fig. 7, I do away entirely with the use of the reinforcing rods. In this form of the invention the strap 8 is bent so that one end forms a semi-circular extension 16 and the opposite end is bent around this semi-circular extension as indicated at 17, and the end thereof extends horizontally as indicated at 18.

From the above detailed description it is thought that the mode of using my insert, as 90 well as the advantages, will be clearly understood. The insert is adapted to be embedded in the concrete and piping or shafting connected thereto. The insert is initially placed upon the form board 1 and temporarily held 100 in position by means of the nail 7 which extends through the vertical opening 6, the socket 4, and engages in the form board. The strap 8 is extended through the slot 5 in such a position that it will engage the 105 closed end of the slot and will be held in this position by the nail 7. If the reinforcing rods are to be used, they are placed and held in proper position and the ends of the strap 8 bent therearound. When this has 110 been done, the concrete is poured upon the form board and will be allowed to set. After

setting, the form board is removed and the nail 7 will be clipped or cut at the top of the socket 4. By having the strap 8 perforated the concrete will pass through the perforations and more securely hold the strap and insert in position. The sides of the insert being inclined will allow the concrete to set around the insert in such a manner that the taper or incline will support said insert in the concrete. The strap 8 and the reinforcing rod form an additional support for the insert and at the same time the strap will also aid in the reinforcing of the concrete.

15 As shown in Fig. 7 of the drawings, it is not absolutely necessary to bend the ends of the strap around the reinforcing rods, and the ends of said strap may be merely bent as shown. The horizontal extension 18 in this 20 form of the invention will aid in supporting the strap and insert.

Having fully described my invention, what I claim as new and desire to secure by Letters Patent of the United States, is:

25 1. A concrete insert having a threaded socket formed in the bottom, a transversely extending slot from one side, and an opening from the top to the socket, the transversely extending slot terminating at a point 30 beyond the opening in the top.

2. A concrete insert comprising a body having a transverse slot extending from one side and terminating adjacent the opposite side, a flexible strap extending through said 35 slot and engaging the inner wall thereof and means extending into the slot and engaging the outer edge of the strap.

3. A concrete insert comprising a body having a transversely extending slot from one side and a vertical opening from the top to the bottom, a flexible strap extending 40 through the transverse slot, and a fastening element extending through the vertical opening.

45 4. A concrete insert comprising a body having a transversely extending slot from one side and a vertical opening from the top to the bottom, a flexible strap extending through the transverse slot, and a fastening 50 element extending through the vertical opening and engaging the edge of the flexible strap.

5. A concrete insert comprising a body having a socket formed in the bottom, a transverse slot extending from one side and

a vertical opening extending from the top through the slot to the socket, a flexible strap extending through the slot, and a fastening element extending through the vertical opening and socket and engaging the edge of the 60 flexible strap.

6. A concrete insert comprising a tapered body of greater diameter at the inner end than at the outer end, having a threaded socket from the outer end and a transversely 65 extending aperture above the socket, and a supporting strap insertable into the transverse aperture of the body.

7. A concrete insert comprising a longitudinally tapered body of greater diameter 70 at the inner end than at the outer end, and a transversely extending slot from one side, adjacent the inner end, and a threaded socket extending from the outer end, a strap adapted to extend through the transversely extending slot, and means extending through the slot for engaging the edge of the strap.

8. A concrete insert comprising a body having a horizontally extending slot from one edge, a strap adapted to extend through 80 the slot with one edge engaging the inner end thereof, and means extending vertically through the body for engaging the outer edge of the strap.

9. An insert comprising a body having a horizontally extending opening from one side, a socket formed in the bottom and a vertical opening extending from the top to the socket, a strap adapted to extend through the horizontally extending opening and engaging the inner wall thereof, and means extending through the vertical opening and socket and extending beyond the end of the insert for temporarily attaching the insert to form a board, said attaching means engaging the edge of the strap for holding the same within the opening.

10. An insert comprising a body, a strap carried by the body, and means extending through the body for securing the insert 100 temporarily to a form board, said securing means engaging the strap for preventing disengagement thereof from the body.

In testimony whereof I have hereunto affixed my signature in the presence of two 105 witnesses.

RAYMOND P. ZENTS.
